T. J. PEACE

AIR HEATER

Original Filed July 7, 1924

Inventor
T. J. Peace

By *Clarence A. O'Brien*

Attorney

UNITED STATES PATENT OFFICE.

THOMAS JEFFERSON PEACE, OF SEDALIA, MISSOURI.

AIR HEATER.

Application filed July 7, 1924, Serial No. 724,642. Renewed November 7, 1925.

To all whom it may concern:

Be it known that I, THOMAS JEFFERSON PEACE, a citizen of the United States, residing at Sedalia, in the county of Pettis and State of Missouri, have invented certain new and useful Improvements in an Air Heater, of which the following is a specification.

This invention relates to an improved heating apparatus which may be more specifically referred to as an air heater, the same being adapted for general house and hotel use.

It is my object to provide a heater of this class wherein the air is circulated through heated drums under the action of a fan so as to insure a constant flow of air from the source to the point of discharge in the room.

It is a feature of the invention to provide a plurality of superposed air heating drums with burners in association therewith, the flames from the burners impinging upon the drums to heat the latter to a high degree so that the air passing therethrough will in turn be intensely heated, these drums and burners being housed within a jacket or casing to obtain the full benefit of the heat from the burners.

Other features and advantages of the invention will become apparent from the following description and drawing.

In the accompanying drawing forming a part of this application and in which like numerals are employed to designate like parts throughout the same:

Figure 1 represents a central vertical section, with parts in elevation, of a heating apparatus constructed in accordance with the present invention.

Figure 2 represents an enlarged detail section through two of the air drums.

Figure 3 is a horizontal section taken approximately on the plane of the line 3-3 of Figure 1.

Referring now to the drawing in detail, the numeral 1 designates a vertically elongated outer casing or jacket which may be made up of two plies of sheet metal of any desirable quality. Although I have not shown this, I propose to interpose asbestos between the plies and metal to render the casing heat-proof. The inner sheet of material is formed at its top to provide an apertured hot air escape dome 2, while the corresponding portion of the outer sheet is

formulated in any manner to provide a suitable hot air discharge 3. Furthermore, if desired, the jacket may be provided at vertically spaced points on one side with transparent windows or doors 4 which may be mounted in any appropriate manner either to permit them to be swung open, slid open, or removed.

As before intimated, the jacket just described houses an air conduit which in the present instance is composed of a plurality of superposed drums 5 and 6. While these drums could be of any suitable configuration other than that shown, they are preferably of the shape shown and are separate and connected together through the medium of a constricted neck, this neck being joined to the body portions through the medium of conical flame spreading surfaces 7. The upper drum is substantially ovate in cross section to provide clearance space between its opposed flattened sides and the adjacent portions of the walls of the casing. The lower drum 5 is supported upon the neck of a hollow base 8 and this base is provided on one side with an air intake 9 in which an electric air circulating fan 10 is located. Although I have not shown it, I propose to attach a cold air conveying pipe to the intake 9, the conveying pipe coming from any suitable source, such as from a register in the floor of the building above. Positioned in the casing between the air drums 5 and 6 is a horizontal partition 11. It will be observed that this partition 11 is provided with apertures to permit passage of effluent particles of combustion therein and downward air currents therethrough. Also, disposed above the upper drum is a rotary damper 12.

Surrounding the joining necks between the drums and the lower drum base are superposed ring-like burners 13. By preference, these will be gas burners and will be provided with a plurality of apertures for causing a circular flame to impinge upon each air drum. The burners are connected together by a pipe 14 and each burner is provided with a control valve 15. The gas supply pipe is indicated by the reference character 16.

Although it is not essential, I propose to utilize the heating drums for the purpose of heating water and in carrying out this end I simply provide a coil 17 for surround-

ing one or more of the air drums as shown, this coil being in communication with a wa-
5 ter reservoir or tank 18 and the discharge end 19 thereof leading to any suitable point of discharge.

From the foregoing it is obvious that the cold air enters the base 8 through the intake 9 and travels upwardly in the direction of the arrows, a forced circulation being pro-
10 duced by the aid of the fan 10. The flame from the burners 13 impinges upon the lower inclined surfaces of the drums 5 and 6 and serves to heat these to a high degree. Consequently, the air passing through these
15 drums will come in contact with the heated walls and will in turn become heated to a high degree before passing out through the discharge passage 8. As before stated, the discharge passage may communicate with
20 one or more radiators in the room or building to be heated. The discharge of the heated air may be controlled more or less by the regulating damper 12. While the drums are serving to heat the air passing there-
25 through, they also serve to heat the water passing from the tank 18 through the coil 17 and pipe 19. In practice, this coil may be of any size or may be applied to both of the drums.
30 Although I have shown and described the specific embodiment of the invention, I wish it to be understood that minor changes coming within the scope of the adjoined claims may be resorted to if desired. For instance,
35 while I have shown but a pair of superposed burners, I wish it to be understood that more than two burners may be used if necessary.

Having thus described the invention, what I claim is:—

1. A heating apparatus comprising a plu-
40 rality of superposed hollow air heating drums connected together through the me-
dium of necks, a hollow base upon which said drums are mounted, said base being pro-
vided with an air intake, superposed ring-
45 like apertured burners surrounding the neck between the drums and the lower drum and said base, a valved fluid supply pipe connect-
ing said burners together, a casing for said drums, said casing being provided with a 50 discharge for the heated air, and a damper mounted in said casing and cooperating with said discharge.

2. A heating apparatus of the class de-
55 scribed comprising a plurality of super-
posed hollow air heating drums, each drum being provided with conical flame spreading
surfaces and with a constricted neck con-
nected to the corresponding part of the ad-
jacent drum, annular apertured burners sur-
60 rounding said neck, a valved fuel supply
pipe connecting said burners together, a
hollow base upon which said drums are sup-
ported, said base being provided with a re-
stricted cold air intake, a circulating fan 65
for the air disposed in said intake, a casing
for the drums and burners supported from
said base, a hot air discharge controlling
damper arranged in said casing, and a hori-
70 zontal partition disposed in the casing be-
tween the upper and lower drums.

In testimony whereof I affix my signature.

THOMAS JEFFERSON PEACE.
